P. S. Caldwell

ATTORNEY.

UNITED STATES PATENT OFFICE.

FRANK A. BIEBERSTEIN, OF MILWAUKEE, WISCONSIN.

VEST.

Application filed April 25, 1927. Serial No. 186,376.

The invention relates to vests and more particularly to lined vests.

In lined vests of ready-made construction, alteration of the side seams is frequently necessary when fitting the individual customer, and this has heretofore been accomplished by ripping the neck seam and turning the vest insideout to gain access to the side seams. This method of alteration entails a 10 certain amount of hand sewing and requires considerable time.

An object of the invention is to provide a vest in which the side seams can be constructed in a simple manner to present a 15 finished appearance and in which alteration of the side seams can be expeditiously made without impairing the finished appearance of the garment.

Another object of the invention is to provide a vest in which the edges of the cloth plies at the side seams can be effectively trimmed without the use of separate piping.

The invention further consists in the several features hereinafter set forth and more 25 particularly defined by the annexed claims.

In the accompanying drawings, Fig. 1 is a side view of the exterior of a vest embodying the invention;

Fig. 2 is a fragmentary view of the interior of the vest;

Fig. 3 is a fragmentary detail perspective view showing the lower end of the side seam before completion;

Fig. 4 is a fragmentary bottom edge view 35 of the vest at the side seam;

Fig. 5 is a transverse sectional view through the seam, taken on the line 5—5 of Fig. 2;

Fig. 6 is a view similar to Fig. 5, showing 40 a modified form of side seam; and

Fig. 7 is a perspective detail sectional view taken along the line 7—7 of Fig. 3.

In these drawings the numeral 10 designates the outer front portion of a vest including the usual pockets 11. The front portion 10 is joined to a back 12 by side seams 13 and shoulder seams 14 each terminating at arm holes 15.

The front portion 10 is provided with an 50 inner facing 16 and a lining 17 of suitable material, and the back 12 is provided with a lining 18 secured at its upper edge by a neck seam 19. The marginal portions of the front and back together with their linings 55 are infolded and sewn along the outer edges

of the vest and around the armholes so as to conceal all raw edges of the cloth plies, the form of construction being indicated at 20 in Figs. 3 and 7.

In the construction of the side seam, the 60 front portion 10 and the back 12 with its lining 18 have their raw edges aligned, while the lining 17 for the front portion 10 has its marginal portion projecting beyond the edges of the remaining cloth plies to 65 form a lip 21, the lip being folded over the edge portions of the remaining plies and constituting a binding, as seen in Figs. 3 and 5, to enclose the edge portions of the remaining cloth plies. A line of stitching 70 22 is then run along adjacent the edges of the cloth plies to bind together the cloth plies and the folded binding lip 21. The side seam 13 is sewn substantially parallel 75 with the meeting edges of the front and back and is spaced therefrom, the back portion 12 and its lining being subsequently folded back along the seam 13 as indicated in Figs. 4 and 5. This reversal of the back and its lining serves to conceal the raw edge 80 of the binding lip 21, and the flap formed by the meeting marginal portions of the front and back is retained in position by short transverse stitchings or tackings 23 near the armhole 15 and the bottom edge of the vest, 85 as seen in Figs. 1 and 2. The tackings 23 may be readily sewn by machine.

In the modified form of the invention shown in Fig. 6, the meeting edges of the back and front and their respective linings 90 are sewn together in alignment by a seam 24 spaced a short distance from the edges of the plies and parallel thereto, the back lining 18 abutting the front lining 17. The back and its lining are then folded to embrace all the 95 edges of the several plies and thereby forms a binding 21' which is sewn to the remaining plies by a seam 22'. The side seam 13 is then sewn substantially parallel with the binding as before and is then folded back 100 in the same manner as in Fig. 5.

When it is necessary to let out the vest at the side seams, the end tackings 23 and side seams 13 are both ripped and the new side seam is then sewn at a proper location 105 closer to the free edge of the flap. New end tackings 23 are then sewn to retain the narrowed flap against the back.

When it is necessary to take in the vest at the side seams, the end tackings and side 110

seams are both ripped and a new side seam is then sewn at a proper location without need for ripping the original side seam, although the latter may be removed if desired. 5 New end tackings are then provided in the same manner as when taking in the vest.

It will be noted that these alterations of the seams are accomplished without necessity for ripping the neck seam and turning 10 the vest inside-out, or of turning the material at the armholes or the lower edge of the vest. The alteration of the side seams, when required, can be accomplished in an inexpensive and expeditious manner without 15 impairing the finished appearance of the vest, and the side seams are of such character as to facilitate the original construction of the vest. By making the binding for the side seam flap integral with one of the lining 20 edges, the use of a separate piping is obviated, which results in certain advantages. First, there is no problem of matching or harmonizing piping material with the vest lining material; the side seam connection 25 at the binding can be made with fewer plies of cloth than when using a piping, and, the ends of the binding can be finished less bulkily.

What I claim as new and desire to secure 30 by Letters Patent is:

1. In a vest, the combination of front and back portions secured together at their meeting edges to form a flap of several plies extending between the armhole and the lower 35 edge of the vest, one of said plies extending beyond the edges of the remaining plies to form a lip folded to embrace the remaining plies, a line of stitching joining said front and back portions to form an alterable side 40 seam and defining the inner edge of said flap, and stitching extending across said

flap at its ends to retain said flap against said back portion.

2. In a vest, the combination of front and back portions and respective linings therefor all secured at their meeting edges to 45 form a flap of several plies extending between the armholes and the lower edge of the vest, one of said linings extending beyond the edges of other plies to form a lip 50 folded to embrace said plies and sewn thereto, and a line of stitching joining said back and front portions to form an alterable side seam and defining the inner edge of said flap.

3. In a vest, the combination of front and back portions having respective linings all secured together at their meeting edges to 55 form a flap of several plies extending between the armhole and the lower edge of the vest, the lining for the front portion extending beyond the edges of the remaining plies to form a part folded to embrace said plies and sewn thereto, and a line of stitching joining said front and back portions to form an alterable side seam and defining the inner edge of said flap.

4. In a vest, the combination of front and back portions at least one of which has a lining and all secured at their meeting 60 edges to form a flap of several plies extending between the armhole and the lower edge of the vest, said lining projecting beyond the edges of other plies to form a lip 65 folded to embrace said plies and sewn thereto, and a line of stitching joining said back and front portions to form an alterable side seam and defining the inner edge of said flap.

In testimony whereof, I affix my signature.

FRANK A. BIEBERSTEIN.
